SANITARY COVER FOR A BODY ORGAN

Earl F. Rightsell, Durham, N. C.

Application February 8, 1937, Serial No. 124,600

2 Claims.

(Cl. 2—21)

This invention relates to a covering or shield for organs of the human body to protect the organ over which the device is placed from contamination and soiling. The purpose of the invention is 5 solely for sanitary purposes and for the prevention of contagious diseases.

When an organ of the human body is inserted into a cavity in another body, there is always danger of contagion even though the organ has 10 a covering thereover as secretions and deposits from said other human bodies may pass beyond the covering on the organ which is being inserted and lodge on the body of the person inserting the organ in a cavity, and results not only in the 15 necessity of thorough washing and sterilization of the portion of the body surrounding the base of the organ but also renders the body of the inserted organ susceptible to the contraction of contagious diseases borne by the body having a cavity 20 into which the organ has been inserted.

As an example, physicians in examining cavities in the human body sometimes insert a finger having an elongated cot thereover into the cavity for inspection purposes, resulting in secretions from 25 the body passing onto the hand of the physician at a point which is not covered by the cot covering the finger. In order to eliminate this source of contamination some physicians use a rubber sack, much larger than the finger which is supposed to 30 fit over the hand also of the physician, but this is clumsy and interferes with the proper inspection of the cavity under survey.

It is therefore, an object of this invention to provide a rubber cot having a disk also of rubber 35 secured to the base of the rubber cot and occupying a plane disposed at right angles to the longitudinal axis of the cot so as to shield the body of the person, when said person inserts an organ of his body into a cavity of another human body, 40 from contamination. The cot or disk, or both may be of a suitable material other than rubber, such as membranous material, which may be diaphanous if desired.

Some of the objects of the invention having 45 been stated, other objects will appear as the description proceeds when taken in connection with the accompanying drawing, in which:—

Figure 1 is a perspective view showing the cot and shield inserted over an organ of the human 50 body and shielding the portions of the body adjacent to the organ from contamination;

Figure 2 is a perspective view showing the position of the device as it is being placed over the 55 organ;

Figure 3 is a longitudinal, sectional view show-

ing the device in fully applied position but omitting the organ within the device and also omitting the body portion of which the organ is a part;

Figure 4 is a vertical, sectional view taken through the device in the position shown in Figure 2;

Figure 5 is a vertical, sectional view showing the device rolled and ready for packing and also ready for installation on an organ of the human body;

Figure 6 shows in section a modified form of the edge of the shield 11, in which the outer edge is thicker than the main part of the disk 11;

Figure 7 shows in section another modified form of the outer edge of the disk 11 in which a reinforcing member 17 is disposed.

Referring more specifically to the drawing, the numeral 10 indicates the cot or tubular portion of the device which has integral therewith and disposed at right angles thereto a shield 11. When 20 the apparatus is manufactured it first has the portion 10 doubled upon itself as shown in Figure 4, and then beginning at point 12 the tubular, doubled portion is rolled upon itself to form a roll 13 as shown in Figure 5. The tip or closed end of 25 the cot 14 would usually be collapsed within the space defined within ring 13 so that the device would occupy very little room in packing and while being transported.

To insert the device over a rigid organ of the 30 human body, it is taken in the position shown in Figure 5 and the end of the organ is placed into the portion 15 then the roll 13 is unrolled until the device is in the position shown in Figure 4 at which time the shield 11 is seized and the same is 35 pulled to the position shown in Figure 3.

It is thus seen that I have provided a sanitary 40 covering for an organ of the human body which also shields the body adjacent the organ from soiling or contamination, and which can be rolled in a novel manner to occupy a very small amount of space when packed for storage or transportation.

In Figure 6 is shown the outer edge of the disk 45 11 in section, and in which said outer edge is much thicker than the main portion of the disk. This gives greater rigidity to the disk 11 and causes to remain in distended position during use. The thicker portion is indicated by 16.

In Figure 7 another means for re-enforcing the 50 rim of the shield 11 is shown, and in which form the shield 11 is rolled around a suitable wire 17 and suitably secured there-around.

In the drawing and specification, there has been 55 set forth a preferred embodiment of the invention,

and although specific terms are employed, they are used in a generic and descriptive sense only, and not for purposes of limitation, the scope of the invention being set forth in the appended claims.

5 I claim:

1. That method of rolling a rubber article having an extended flexible sack and a disk of flexible rubber integral with the open end of the sack and 10 being disposed in a plane disposed at substantially right angles to the longitudinal axis of the sack, which comprises telescoping the sack until its closed end projects through the open end of the

sack, then rolling the telescoped portion of the sack until the roll rests against one side of the disk.

2. A rolled rubber article comprising an elongated sack having an open end and a closed end 5 and having an annular base portion whose inner edge is integral with the open end of the sack, the sack being telescoped so that its closed end protrudes slightly through the open end of the sack and the telescoped portion of the sack being 10 rolled to where the rolled portion lies adjacent one side of the base portion.

EARL F. RIGHTSELL.
